CHARLES W. STAFFORD, OF SAYBROOK, CONNECTICUT.

Letters Patent No. 63,664, dated April 9, 1867.

IMPROVED GARBAGE AND ASH-BOX.

The Schedule referred to in these Letters Patent and making part of the same.

TO ALL WHOM IT MAY CONCERN:

Be it known that I, CHARLES W. STAFFORD, of Saybrook, in the county of Middlesex, and State of Connecticut, have invented a new and improved Elevating and Self-Dumping Garbage and Ash-Box; and I do hereby declare that the following is a full, clear, and exact description thereof, which will enable others skilled in the art to make and use the same, reference being had to the accompanying drawing, forming a part of this specification, in which—

Figure 1 is a side sectional view of my invention, taken in the line $x x$, fig. 2.

Figure 2 is an external front view of the same.

Similar letters of reference indicate like parts.

The object of this invention is to obtain a receptacle for garbage and ashes, which may be placed on the edge of a sidewalk in front of a residence, and not have any unsightly appearance, and be capable of having its contents dumped by a single person into a cart with the greatest facility.

A represents a case, in which the garbage and ash-box is fitted or enclosed. This case is of cast iron, and may be of any neat or ornamental pattern; and it is provided with a lid or cover, B, attached by a hinge. This case is cast with a suitable base, a , and a hollow post, C, dependent therefrom, the post passing through a hole in the flagging down into the earth, and the base a resting or bearing on the flagging, as shown clearly in fig. 1. D represents the garbage or ash-box, which may be constructed of sheet or cast metal. If of the former material it may have a cast-iron rim at the top. The shape of the box D conforms to that of the case A; and the bottom of D is connected by a hinge or joint, b, to a rod, E, which slides freely within the hollow post C of the case A. This rod E is cast with a vertical rack, c, in which a pinion, F, gears, said pinion being on a shaft, G, which is fitted in a bearing, d, cast with the case A. One end of the shaft G is formed with a square, to receive a crank, H, by which the shaft is turned. I is a chain, one end of which is attached to the box D near its centre, the other end being attached to the bottom of a chamber, e, cast with the case A. The top of the garbage or ash-box is provided with a rim, f, to rest on the top of the case A, and the lid or cover B, when down, rests on the rim f. Garbage or ashes are thrown into the box D at any time by raising the lid or cover B; and, when the contents of D are to be removed, the shaft G is turned by means of the crank H, the cart, shown in red, being backed up in front of the case A. By turning the shaft G in the proper direction, as indicated by arrow 1, the box D is raised, in consequence of the pinion F gearing into the rack c of the rod E; and, when the bottom of the box D nearly reaches the top of the case A, the chain I will be fully distended, and will check the ascent of the box D, causing the latter, as the rod E is forced upward, to tilt or dump over the top of a , and discharge its contents into the cart, as shown in red in fig. 1. On turning the shaft G in the reverse direction, the box D will turn up to a vertical position, and descend within the case A. By this simple arrangement it will be seen that garbage and ashes may be kept within a covered receptacle on the edge of the sidewalk without any trouble or inconvenience whatever, and the contents removed or dumped into a cart by a single person with the greatest facility.

Having thus described my invention, I claim as new, and desire to secure by Letters Patent—

1. A garbage or ash-box, placed within a case provided with a lid or cover, and arranged, as herein shown and described, to admit of being elevated and tilted or dumped, in order that its contents may be discharged into a cart, substantially as described.

2. The rod H, attached to the bottom of the garbage or ash-box D, and provided with the rack c, the hollow part C of the case A, in which the rod H works, the pinion F on shaft G, and the chain I, all arranged to operate in the manner substantially as and for the purpose set forth.

The above specification of my invention signed by me this 17th day of August, 1866.

C. W. STAFFORD.
